UNITED STATES PATENT OFFICE.

EARLE W. CUMMINGS, OF SANTA BARBARA, CALIFORNIA.

CASEMENT-WINDOW MOUNTING.

Application filed August 23, 1926. Serial No. 130,895.

This invention relates to swingingly mounted sash frames, or what are generally known as casement window mountings, tho in fact applicable to swinging sash frames 5 operating in any plane.

The objects of the invention are to provide mounting means of the character mentioned which is particularly adapted for use with casement window frames, which will surely hold the window at various points of 10 adjustment and which will be adapted for operation on windows without disturbing any fly screen frames which may be in place at the time of operation.

15 In the drawings hereto Figure 1 is a perspective view of the lower part of a window frame and out-swinging sash equipped with my mounting and adjusted to partially opened position.

20 Figure 2 is a perspective view of the lower part of a fly screen in vertical alignment with the window frame of Figure 1 to indicate how it would fit therein.

Figure 3 is a reduced diagrammatic plan 25 view of my mounting applied to a sash to indicate its operation, while Figure 4 is a similar view showing the sash closed.

Figures 5 and 6 are respectively enlarged 30 plan and side views of my adjusting screw and connections.

Figures 7 and 8 show optional variations in construction of the adjusting screw.

Briefly described my invention comprises 35 a pair of parallel levers pivotally attached to the window frame at one end of the levers and at the other end to the swinging sash—or in fact two such pair of levers, as it is intended that for casement windows a pair be at the bottom of the sash and another pair at the 40 top, or for transom type of windows a pair on opposite vertical edges thereof.

In either case but one pair of the levers 45 require the adjustment control, and since they are alike in other respects the pair having the adjustment control only is shown in the drawings, it being understood that a similar pair (of opposite hand as regards right and left) is in alignment therewith at the opposite edge of the window frame, and 50 that the adjustment control is omitted.

In the drawings 1 represents the window sill of a window frame 2 provided on the far side with an outswinging casement sash 3. This sash 3 is supported at top and bot-

tom by a pair of levers as at 4 and 5 pivotally mounted at their inner ends to a sill plate 6 screwed to the window frame or sill, and at their outer ends to a sash plate 7 attached to the sash as shown.

These levers are rigid enough to carry the full weight of the sash, thereby taking the place of hinges, and when swinging the sash they function similarly to a pair of parallel levers tho with the difference due to the lever 5 being shorter than the lever 4, that as the sash is swung outward at the left side the right side is pulled inward and retained nearer the sill than would otherwise be the case. This action maintains a smaller space between the near edge of the sash and window frame, (as at A in Figure 2) when the window is open, thereby giving a relatively large main opening yet providing the smaller opening A to facilitate washing the outer side of the glass. The dotted lines in Figure 3 indicate the full open position of the sash.

The levers have their pivotal points closer together on the sash than on the window frame and one of the levers is suitably positioned or offset as at B so as not to interfere with the other lever when the sash is closed to the position of Figure 4.

To effect a control of the levers various artifices may be resorted to, but my preferred arrangement is to provide a screw 9 swivelly engaging a socket member 10 pivoted to the lever 4 and passing through a threaded nut 11 vertically pivoted to the plate 6 at 12.

This screw projects substantially at right angles to the sash inward into the room when the sash is closed, and in case of using a fly screen on the window the screw projects through a hole in the lower stile of the same.

Figure 2 indicates such a screen adapted to fit into the window frame against the stops 13 and provided with a hole 14 adapted to pass over the screw, and since the hole is made sufficiently large and the angular lateral movement of the screw is very little near the nut 11, no interference results and the screen may either be left in place while operating the device or freely removed at any time by simply releasing the retaining buttons 15.

To operate the screw, any suitable small

crank wrench is provided which will fit over the square end of the screw and will clear the inner edge of the window sill so that it may be revolved without striking the sill. Such a crank wrench is indicated in place on the screw at 16 and is shown in dotted lines so as not to confuse the drawing.

Several modifications in the screw mounting suggest themselves, as for instance the 10 employment of a ball and socket connection 17 of the screw to the lever 4 as shown in Figure 7, or of simply pivoting the screw to the lever 4 so that the screw cannot revolve, as in Figure 8, and providing a sleeve 15 nut 18 engaging the screw and provided with flanges 19 revolvably retaining it in the blank vertically pivoted pedestal 11' and having an extension 18' adapted for turning with a special wrench, so that by revolving the sleeve nut 18 the screw will be forced 20 back and forth to operate the sash.

It is of course understood that the levers are to be made in right and left sets to provide for windows swinging in either direction, also that they may be applied to transom type windows, and that in either case the mounting is positioned closer to the edge of the window controlled by the shorter lever so as to hold that edge relatively 25 close to the window frame at all times to reduce the effect of heavy winds.

With my device as described the sash requires no special fittings or shaping of its edges, nor does the frame or sill require any 30 special construction of any kind, and the 35

sash is firmly locked in all positions of adjustment against any attempt to move it.

I claim:

1. A mounting for a swinging window of the character described comprising a pair of spaced levers at each of opposite aligned points of the sash adjacent the edge of same, each pair of levers being pivoted to the sash at one end of the levers and to the window frame at the opposite ends and with similar pivotal points of both pairs of levers in alignment, and means operative on one of the levers for positively forcing same to swing, for swinging the sash. 40

2. A mounting for a swinging window of the character described comprising a pair of spaced levers at each of opposite aligned points of the sash adjacent the edge of the same, each pair of levers being pivoted to the sash at one end of the levers and to the window frame at the opposite ends and with similar pivotal points of both pairs of levers in alignment, and screw means operative on one of the levers for positively forcing same to swing, for swinging the sash. 45

3. A structure as specified in claim 2 in which said screw means is operative through an opening provided in a screen frame placed in the window frame. 50

4. A structure as specified in claim 1 in which a screw is provided with swivel connection to one of said levers and is supported on said frame. 55
